UNITED STATES PATENT OFFICE.

SARAH C. MORRILL, OF NEW YORK, N. Y., EXECUTRIX OF CHARLES MORRILL, DECEASED.

DESIGN FOR A LEVER-HANDLE.

SPECIFICATION forming part of Design No. 34,074, dated February 12, 1901.

Application filed December 31, 1900, Serial No. 41,744. Term of patent 3½ years.

To all whom it may concern:

Be it known that CHARLES MORRILL, deceased, late of the city of New York, borough of Manhattan, and State of New York, did invent and produce a new and original Design for a Lever-Handle for Bench-Punches, of which the following is a specification, reference being had to the accompanying drawings, forming part thereof.

10 Figure 1 represents a side elevation of the lever-handle. Fig. 2 represents a transverse section of the lever-handle, taken on line X X of Fig. 1.

As shown in the drawings, the leading or 15 material feature of the design consists of the depending portion A, the contour of which forming what is usually termed in mechanics a "deerfoot," formed by the union of different-sized circular lines or edges B, C, and D.

20 The largest of the said circular lines or edges joins a vertically-inclined straight line or edge, the latter of which terminates in a circular line E and continues until it joins a horizontal line or edge F. This line F terminates in a cylindrical but oblong-shaped

25 handle G. The lower line or edge H of the lever inclines slightly downward and terminates in the circular line or portion I, which in turn continues in a straight line K and joins with the circular portion D, thus forming the contour of the entire device. The body of the lever is formed by the depression L, which leaves projecting therefrom the beads or ribs M.

The plane surface bounded by the circular 30 portion B is provided with the circular perforation N, while the plane surface bounded by the circular portion D is provided with a smaller perforation P.

Having described the invention, what is 35 claimed as new, and desired to be secured by Letters Patent, is—

The design for a lever-handle as herein shown and described.

SARAH C. MORRILL,
Executrix of the estate of Charles Morrill,
deceased.
